UNITED STATES PATENT OFFICE.

WELLS R. STOKELY, OF ST. AUGUSTINE, FLORIDA.

EGG-CARRIER.

No. 902,697.

Specification of Letters Patent.

Patented Nov. 3, 1908.

Application filed September 24, 1907. Serial No. 394,297.

To all whom it may concern:

Be it known that I, WELLS R. STOKELY, citizen of the United States, residing at St. Augustine, in the county of St. Johns and 5 State of Florida, have invented new and useful Improvements in Egg-Carriers, of which the following is a specification.

My invention pertains to cylindrical shipping boxes for carrying eggs and more particularly to the egg-holders contained in such boxes; and it consists in the peculiar and advantageous construction hereinafter described and particularly pointed out in the 10 claim appended.

15 In the accompanying drawings, forming part of this specification: Figure 1 is a diametrical section of a cylindrical box containing superposed egg-holders constructed in accordance with my invention. Fig. 2 is a plan view of one of the egg-holders, removed. 20 Fig. 3 is a fragmentary perspective view of the same.

Similar letters designate corresponding parts in all of the views of the drawings, referring to which:

A is the body of a cylindrical box which is preferably perforated as indicated by *a* and provided with hoops *b*.
B B are heads which are perforated at *c* and are preferably, though not necessarily, constructed in accordance with the invention forming the subject matter of my contemporary application of even date herewith, Serial Number 394,295, and C C are my novel egg-holders which are superposed or arranged one above the other in the body A and between the heads B, and are removable individually therefrom.

As best shown in Figs. 2 and 3, the egg-holders C respectively comprise a circular rim *d*, of pasteboard or other suitable material, circular series of tubular cells *e*, of pasteboard or other suitable material, glued or otherwise connected together, glue *f* or other suitable means connecting the cells *e* in the outer circle to the rim *d*, and a central, circular cell *g*, of pasteboard or other suitable material, glued or otherwise connected to the cells *e* in the inner circle, and designed for the passage of air as will be presently pointed out. It will be readily apparent that a holder constructed as just described will hold a large number of eggs in separate cells within a given circular area, and this in such manner that shock or jar imposed on one cell will not be transmitted to the other cells; and it

will also be apparent that each holder C may be lifted, lowered and otherwise handled as a unit.

In addition to the elements mentioned, I prefer to have each of the holders C comprise a bottom *h*, of pasteboard or other suitable material, this in order that the holder may be handled after the manner of a tray to carry a horizontal course of eggs. The said bottom *h* is provided with a central aperture *i* in alignment with the central cell *g*, and is preferably, though not necessarily, glued or otherwise connected to the lower ends of the cells *g* and *e*, and is either formed integral with the rim *d* as shown or is glued or otherwise fixed to said rim in the discretion of the manufacturer.

When desirable the central or air cell *i* may be omitted and the space within the inner circular series of cells *e* utilized for the conduct of air without involving departure from the scope of my invention as defined in the appended claim.

In the practical use of my improvements the holders C containing eggs in their cells *e* are superposed or arranged one above the other in the box as shown in Fig. 1, and when the holders are thus arranged it will be apparent that a central, vertical conduit is afforded in communication with the openings *c* in heads B and through which air is free to pass from the opening in one head to the opening in the other head, thus assuring adequate ventilation of the eggs. It will also be apparent that when the upper head B is removed, the holders C may be lifted one by one from the box and used after the manner of a tray to hold the eggs while the same are being inspected by a prospective purchaser, or as a convenient means of carrying the eggs from one part of a store to another. Again it will be noted that when it is desired to remove eggs from the box in the ordinary manner it is simply necessary to invert the box so as to make the bottom *h* of the lower holder in Fig. 1 uppermost. With this done, it will be seen that when the holder mentioned is lifted, its complement of eggs will be left on the bottom of the next adjoining holder, and may be readily picked up therefrom. This operation may obviously be repeated until all of the holders and all of the eggs are removed from the box.

It will be gathered from the foregoing that in addition to being simple and inexpensive, and calculated to compactly carry a large

number of eggs in safety and in good condition, my improvements facilitate both the packing and the unpacking of the box so that either operation may be effected expeditiously and with but little labor.

Having described my invention, what I claim and desire to secure by Letters-Patent, is:

The combination with a box comprising a cylindrical body and lower and upper heads having openings; of egg-holders superposed in the box and each having a horizontal course of circular series of cells the meeting portions of which are permanently connected together and the lower ends of which are

open, a rim surrounding the outer circular series of cells and permanently connected thereto, and a bottom permanently connected to the rim and resting under the cells and also having a space within the inner circular series of cells and a central opening in the bottom for the passage of air. 20

In testimony whereof I have hereunto set my hand in presence of two subscribing witnesses.

WELLS R. STOKELY.
